METHOD AND MACHINE FOR BUILDING
TIRES

Will C. State, Akron, Ohio, assignor to The Good-year Tire & Rubber Company, Akron, Ohio, a corporation of Ohio

Original No. 1,785,659, dated December 16, 1930,
Serial No. 339,371, February 12, 1929. Application
for reissue November 2, 1932, Serial No.

26 Claims. (Cl. 154—10)

This invention relates to the manufacture of pneumatic tire casings for vehicles, and it has particular relation to a machine for and method of assembling the tread element and the various plies of fabric embodied in such casings.

One object of the invention is to provide a tire building machine in which the use of rollers for stitching the various plies of which the tire is composed, is obviated.

Another object of the invention is to provide a simple mechanism for transporting and correctly centering the various plies of which the tire carcasses are composed with respect to the carcass.

Heretofore, in the manufacture of pneumatic tires, it has been customary to employ some form of core, either of cylindrical or of toroidal contour, upon which the various plies of which the tire carcasses are composed were assembled. In manufacturing tires in accordance with this method, the various plies consisting of rubber or rubberized material were disposed loosely upon the form, and were then stitched together by pressing a small roller or disk against the surface of the ply while the form was being rotated. This method was relatively slow, because considerable time was consumed in the stitching operations. Also, since the form or core was of the same external diameter as the internal diameter of the tire carcass, it was relatively difficult to slip endless bands of fabric, such as frequently used in the construction of tires, over the form.

In a machine constructed in accordance with this invention, the plies or bands are disposed individually or in groups upon a deflated pneumatic tube which is secured upon a cylinder or drum. The drum supporting one or more plies is then thrust forward by means of suitable mechanism into a ring of hollow construction, where the pneumatic tube is inflated to press all portions of the plies against the inner surface of the ring. A vacuum or partial vacuum is then created by convenient means between the inner surface of the ring and outer surface of the ply, thus effectually securing the ply or plies in such position as to permit deflation of the tube, retraction of the drum and application of the remaining plies.

For a better understanding of the invention, reference may now be had to the accompanying drawing, forming a part of the specification, of which

Figure 1 is a view, partially in cross-section and partially in elevation, of one embodiment of the invention; and

Figure 2 is an elevational view of the vacuum ring employed to receive and support the various plies of which the tires are composed.

In practicing the invention, a transfer device comprising a base 11 is provided upon one side 5 thereof with a bracket 12, having a pintle 13 projecting therefrom. The latter element functions as a pivot for a bracket or lug 14 upon the rear end of a cylinder 15. Opposite ends of the latter are connected to suitable sources of compressed fluid, such as air or steam, by means of conduits 16 and 17.

From the forward end of the cylinder projects a piston rod 18, which is pivotally attached at 19 to a lever 21. The lower end of the lever, in turn, is pivoted at 22 to the forward end of a link 23, which is hinged, as indicated at 24, to a bracket 26 secured to the side of the base 11. The upper end of the lever 21 is pivoted by means of a pin 27 to a bracket 28, rigidly mounted upon the side 20 of a sliding block 29, that reciprocates in guide-ways 31 formed in the upper surface of the base 11.

A horizontal shaft 32 is secured to the forward face of the sliding block 29, and projects forwardly through a supporting bearing 33 formed in an upstanding bracket 34 attached to the forward face of the base 11. The forward extremity of the shaft is keyed within a hub portion 36 of a drum 37 having marginal flange portions 38, 30 which serve to confine an endless pneumatic tube 39. In order to inflate the tube, a valve 41 is inserted in openings formed in the inner periphery thereof and in the drum 37, and is connected at its outer end to a flexible conduit 42 which is 35 attached to a suitable source of supply (not shown) of compressed fluid.

In order adjustably to limit the extent of travel of the block 29 and the drum 37, upstanding lugs 43 and 44 are provided respectively upon the 40 upper extremities of the bracket 34 and the block 29. One of these elements, for example lug 43, is bored and threaded to receive an adjustable stop screw 46 disposed in the path of movement of the lug 44.

A device 50 for supporting the tire carcasses during the process of assembly is disposed in alignment with the transfer drum 31. This device comprises a base or stand 51 having horizontally extending arms 52 to the ends of which 50 upstanding brackets 53 are attached. The upper portions of these brackets are provided with bearings 54, within which are journalled trunnions 56 and 57 of a ring or annular supporting device 58. As best shown in Figure 1, this device is 55

formed with a circumferentially extending chamber 59, which communicates, by means of a series of small openings 61, formed at regular spaced intervals in the inner wall of the annular member, with a series of peripherally extending grooves 62 formed in the inner surface of said member. The chamber 59 is connected to suitable means (not shown) for creating a vacuum by means of a conduit 63 which communicates 10 with the chamber through the hollow trunnion 57.

In order to alter the position of the ring 58, the bracket 53 is formed with a laterally projecting lug 64, which is bored to receive a spring 15 actuated latch bolt 66, that may be projected into engagement with any one of a series of radially arranged openings 67, formed in a boss-like portion upon the ring 59 adjacent the trunnion 51.

20 In the operation of this apparatus, a tread ply 70 of a tire is first disposed about the pneumatic tube 39. If desired, the ply may be formed into an annulus, and then slipped endwise over the drum 37, or it may be taken as a strip or 25 band and wound about the drum. After the application of the tread ply, compressed fluid is admitted into the cylinder 15 to actuate the piston 18, thereby causing forward movement of the block 29 and the drum 37 until the tread ply 30 is correctly centered within the ring 58.

Compressed fluid is then admitted through the conduit 42 to the pneumatic tube or annulus 39, thereby expanding the latter member and causing the outer circumference of the tread ply to 35 be pressed against the inner walls of the annulus 58. Upon the application of vacuum to the chamber 59, the ply is caused to adhere to the inner circumference of the ring. The tube 39 is then so deflated that the drum 37 may be 40 retracted from the annulus, leaving the tread ply securely held within the annulus by the pressure created by the vacuum.

The breaker strips and various plies of fabric 45 may then be disposed in turn upon the outer circumference of the tube 39, and transported to position within the inner circumference of the tread band. Application of pressure within the tube 39 causes the outer periphery of each ply 50 to be pressed against the inner surface of the preceding ply to which it then adheres, due to the relatively tacky character of the unvulcanized rubber of which the plies are formed or with 55 which they are treated. It will be apparent that the application of pressure within the relatively flexible tube or annulus 39 will cause the bag to expand and press substantially uniformly against all portions of the ply which encircles it. In this way, adhesion is obtained between the various plies without the necessity of applying a 60 stitcher roller thereto.

Since the bead rings of pneumatic tires are relatively narrow and inflexible, it is desirable to place these elements in position by manual operation rather than by mechanical means. This 65 labor is greatly facilitated by releasing the latch bolt 66 and rotating the annulus 58 to the horizontal position indicated in broken lines in Figure 1. The annulus is held in this position by disposing the latch bolt 66 into the proper opening 67. The operation of turning the edge portions of the plies in about the beads is also accomplished by means of a convenient manually operated tool, while the ring 58 is in a horizontal position. After a tire band has been completed, 70 the vacuum in the chamber 59 is released, thus

75 permitting the band to be removed from the forming ring.

The tread portions of pneumatic tire bands thus assembled may be expanded to the toroidal form requisite in pneumatic tires, by placing 5 them upon any convenient shaping device. Also, vulcanization of the bands is performed in the usual manner.

From the foregoing description, it will be apparent that an extremely simple device has been 10 provided for the assembly of pneumatic tires, by employment of which the use of stitcher rollers is obviated. Furthermore, since the tube 39 may be deflated practically to any desired extent, it is a relatively easy task so to reduce its size as 15 to permit the various plies of material to be accurately centered thereon. By adjustment of the screw 46 it is possible so to limit the motion of the block 29 that the plies are then accurately centered with respect to the inner circumference of the ring 58 before the tube 39 is 20 expanded to press the plies into position.

Although I have illustrated only one form 25 which the invention may assume, and have described in detail only a single application thereof, it will be apparent to those skilled in the art that the invention is not so limited but that various modifications may be made therein without departing from the spirit of the invention or 30 from the scope of the appended claims.

What I claim is:

1. A method of constructing pneumatic tires which comprises supporting the outer plies of which the tires are composed by their outer surfaces, and then successively applying the various 35 inner plies to the inner face of the outer ply, the order of the plies with respect to the central axis of the tire being the same during the construction as in the finished tire.

2. A method of constructing pneumatic tires 40 which comprises supporting the outer plies of which the tires are composed by their outer surfaces, successively applying the various inner plies to the inner face of the outer ply, and securing the successive plies into position by the application of radially outwardly directed force. 45

3. A machine for constructing flat built pneumatic tire casings comprising means for supporting the tread ply of a pneumatic tire casing by 50 its outer periphery, means successively to insert the inner plies within the inner circumference of the tread ply, and means adapted to bond each successive ply against the inner circumference of the preceding ply. 55

4. A machine for constructing flat built pneumatic tire casings comprising means for supporting the tread ply of a pneumatic tire casing by 55 its outer periphery, mechanism successively to insert the inner plies within the inner circumference of the tread ply, said mechanism including a pneumatic annulus adapted to be inserted within the tire carcass and adapted to bond each successive ply against the inner circumference of the preceding ply. 60

5. A machine for constructing a flat built 65 pneumatic tire in band form comprising a ring for receiving and supporting the bands, of which the tire is composed, means for creating a vacuum between the inner surface of the ring and the outermost band, and means for first inserting the 70 bands within the ring and thereafter expanding the bands within the ring to bond them together.

6. A machine for constructing a flat built 75 pneumatic tire in band form comprising a ring

for receiving and supporting the bands, of which the tire is composed, vacuum means for drawing and supporting the outer surface of the outermost band against the inner surface of the ring, 5 and an axially movable pneumatic tube connected with a source of compressed fluid adapted for inserting and bonding the bands within the ring.

7. A machine for constructing flat built pneumatic tires comprising a circumferentially chambered annular ring having openings extending through the inner walls of the ring and communicating with the chambered portion thereof, means for creating a vacuum within the chambered ring, and means for first inserting plies 10 of tire material within the ring and thereafter expanding said plies within the ring to bond the plies together.

8. A machine for constructing flat built pneumatic tires comprising a circumferentially chambered annular ring having openings extending through the inner walls of the ring and communicating with the chambered portion thereof, means for creating a vacuum within the chambered ring, and means including an axially movable pneumatic tube adapted for inserting and bonding plies of tire material within the inner circumference of the ring.

9. A machine for constructing pneumatic tires comprising a support, a hollow ring having openings formed in its inner wall communicating with the hollow portion thereof, means for journaling the ring upon the support for movement about a horizontal axis perpendicular to the axis of the ring, means for creating a vacuum in the hollow ring, and means for inserting and expanding plies of tire material within the ring.

10. A machine for constructing pneumatic tires comprising a support, a ring having an annular chamber therein, means for journaling the ring upon the support for movement about a horizontal axis perpendicular to the axis of the ring, said ring having openings formed in the inner wall thereof and communicating with said chamber, means for creating a vacuum in the chamber, 45 and means including an axially movable, expandible pneumatic tube for inserting and expanding plies of tire material within the ring.

11. A method of constructing pneumatic tires which comprises supporting the outer plies of 50 which the tires are composed by their outer surfaces, and then applying the various inner plies to the inner periphery of the outer ply, the order of the plies with respect to the central axis of the tire being the same during the construction as in the finished tire.

12. A method of constructing pneumatic tires which comprises supporting the outer plies of 55 which the tires are composed by their outer surfaces, applying the inner plies to the inner periphery of the outer plies and securing the plies into position by the application of radially outwardly directed force.

13. The step in the method of constructing a 60 pneumatic tire which comprises bonding together substantially the entire opposed surfaces of at least two of the plies of which the tire is composed by the application of radially outwardly directed force applied substantially simultaneously to all portions thereof.

14. The steps in the method of constructing a 65 pneumatic tire which comprise assembling in endless band form and in unbonded relation at least two of the plies of which the tire is composed, and then bonding said plies throughout

their entire opposed surfaces by compacting them against an encircling surface.

15. The steps in the method of constructing a pneumatic tire which comprise assembling in 70 endless band form and in unbonded relation at least two of the plies of which the tire is composed, placing said bands within a ring, and forcing said bands against said ring by an inflatable former acting against the inner face of the inner band throughout its extent.

16. In tire building apparatus for constructing a flat built pneumatic tire, in combination, a chamber having an unyielding inner wall, means for supporting a plurality of unbonded tire constructional units in said chamber, and means 15 adapted to bond said units together by forcing them against each other throughout substantially their entire opposed areas and against said inner wall.

17. In tire building apparatus for constructing 20 a flat built pneumatic tire, in combination, means for supporting in endless band form and in unbonded relation at least two of the plies of which the tire is composed, and means adapted to bond said plies by forcing them against each 25 other throughout substantially their entire opposed areas and against an encircling surface.

18. In tire building apparatus of the character described, in combination, a substantially annular chamber having an unyielding inner wall, 30 a reciprocating member having an expansible outer surface adapted to support a plurality of unbonded tire constructional units, means for centralizing said member in said chamber, and means for expanding said outer surface to force 35 the units against the chamber wall.

19. The steps in the method of constructing a pneumatic tire which comprise assembling in 40 endless band form and in unbonded relation at least two of the plies of which the tire is composed, placing said bands within a ring and forcing said bands against said ring by an outwardly directed force against the inner face of the band throughout its extent.

20. The steps in the method of building a pneumatic tire which comprise arranging substantially cylindrical bands, one within the other, within an encircling ring having a surface, the transverse cross-section of which is substantially complementary to the outer surface of the outermost 50 one of the bands placed within said encircling ring and forcing all of said bands outwardly against said encircling ring and against each other under sufficient pressure to bond said bands together substantially throughout their entire opposed 55 areas.

21. The steps in the method of building a pneumatic tire which comprise arranging a band within and against an encircling surface and holding the same thereagainst, arranging a second band 60 within the first band, and forcing said bands into bonded relation with each under pressure applied to said bands simultaneously in an outward direction, said first band having the outer surface thereof shaped substantially complementary to 65 the inner surface of the encircling ring prior to inserting said first band within and against said ring whereby to maintain said band extended but without distortion against the inner surface of said ring.

22. The method of forming tires comprising the steps of holding the band forming the tread ply thereof in extended position without material distortion, inserting one or more plies within said extended tread ply and bonding said plies to- 75

gether throughout their entire opposed areas by outwardly directed pressure against said plies.

23. The method of forming tires comprising the steps of holding the band forming the tread ply thereof in extended position without material distortion, inserting a plurality of plies within said extended tread ply and bonding said plies together throughout their entire opposed areas by outwardly directed pressure against said plies, 10 said plies being inserted within and bonded to the inner surface of the preceding ply, successively.

24. The method of forming tires comprising the steps of holding the band forming the tread ply thereof in extended position without material distortion, inserting a plurality of plies within said extended tread ply and bonding said plies together throughout their entire opposed areas by outwardly directed pressure against said plies, 15 said plurality of plies being inserted within the outermost ply and bonded thereto and to each other simultaneously.

25. The method of forming tires comprising the steps of forming a ply band on a substantially cylindrical surface, moving said band while still 20

on said surface into concentric relationship in an encircling ring shaped substantially complementary to the outer surface of said band, and forcing said band under pressure into engagement with said ring with the complementary surfaces 5 interfitting and holding said band firmly against said ring while said cylindrical surface is moved out of concentric relation to a position where a second band may be formed thereon, similarly forming one or more bands, successively moving 10 them into concentric relation with respect to said ring, and bonding said bands in superimposed relation throughout substantially their entire opposed areas.

26. A method of constructing a pneumatic tire 15 which comprises arranging a plurality of similarly shaped flat bands in close concentric relation with each other and forcing substantially all portions of their opposed surfaces simultaneously 20 into bonded relation with each other by an outwardly directed force acting simultaneously at all points about the inner periphery of the innermost of said bands.
